I. BENJAMINS

MEANS FOR SECURING WINDOW SASHES IN POSITION

Filed March 15, 1921

FIG. 1.

FIG. 2.

FIG. 3.

Inventor
Israel Benjamins.
By Attorney

Patented July 3, 1923.

1,460,361

UNITED STATES PATENT OFFICE.

ISRAEL BENJAMINS, OF BROOKLYN, NEW YORK.

MEANS FOR SECURING WINDOW SASHES IN POSITION.

Application filed March 15, 1921. Serial No. 452,457.

To all whom it may concern:

Be it known that I, ISRAEL BENJAMINS, a citizen of the United States, residing at Brooklyn, in the county of Kings and State 5 of New York, have invented a new and useful Means for Securing Window Sashes in Position, of which the following is a specification.

My invention consists in the novel features hereinafter more fully described, and the objects of my improvement are:

First: To enable either or both of the sashes of a window to be secured in any required position, thereby insuring against 15 the ingress of burglars and the falling out of children therethrough;

Second: To enable the securing of the window sashes to be accomplished by a single stroke or movement of the hand, also the releasing of the window sashes to be accomplished in the same way; and

Third: To have said means light, simple, durable and inexpensive.

I attain these objects by the device illustrated in the accompanying drawings or by any mechanical equivalent or obvious modification of the same.

In the drawings Fig. 1 is a front view of my means for securing window sashes in position; Fig. 2 is a side view, from left to right in Fig. 1, of the same; Fig. 3 is a section on the line A—B of Fig. 1.

Similar numerals refer to similar parts throughout the several views: 11 designates 35 a tubular member having at one end thereof the shoulder 11^a abutting against the plate 16 and the flange 11^b expanded into the recess 16^a of said plate 16; the main body of said member 11 is threaded to fit the nut 12, and said member terminates at the other 40 end in the prism 18 which is shown in Fig. 1 as octagonal, but which may have any other shape, and which fits the opening in the handle or wrench 19.

Said nut 12 is provided with a base 13, which may be secured to the top of the inner sash 14 by means of suitable wood screws through the screw holes 15.

The plate 16 is adapted to bear against 50 the outer sash 17 when the member 11 is moved forward by turning the handle 19 in the proper direction, thereby pressing the sashes 14 and 17 against the weather strips 21 and 20 respectively.

55 The force applied to the handle 19 is mul-

tiplied by the screw thread until the frictional resistance to moving the sashes is sufficiently great to secure them in place.

22 designates part of the jamb, and 23 the inner guide strip; 24 and 25 are the 60 grooves for the sash cords to pass therethrough.

It is evident that, when the pitch of the thread on the member 11 is large enough, a single stroke or turning movement of the 65 handle 19 through an arc of less than 180 degrees will advance the plate 16 sufficiently to lock the sashes in position.

By making the member 11 tubular greater 70 lightness is secured for a given diameter and pitch thereof.

The handle 19 may be either permanently secured to the member 11 or made detachable when it is desired to prevent children from manipulating the same; the handle 19 may 75 also be made in one with said member 11.

Where the flange 11^b may be expanded sufficiently, the plate 16 may be omitted, although the operation of the device would be more perfect with the plate 16 than without it.

I prefer to have the plate 16 freely swivelled on the end of the member 11 between the shoulder 11^a and the flange 11^b; but it 85 may also be fastened thereto.

Many other changes could be made in my means for securing window sashes in position without departing from the main scope of my invention.

I do not, therefore, restrict myself to the 90 details as shown; but I intend to include also all mechanical equivalents and reasonably obvious modifications of the same within the scope of my claims.

What I claim as my invention, and desire 95 to secure by Letters Patent is:

1. In a means for securing window sashes in position a tubular member terminating at the inner end thereof in a prism, a thread of a suitable pitch on the exterior of said member, a nut adapted to fit said thread, and to be secured to the inner sash a handle having therein a prismatic opening whereby it may be detachably connected to said member and adapted to turn the same through part of a 100 revolution and to cooperate with said thread and nut to advance said member, by its motion through a part of a revolution, and to cause it to bear against the outer sash.

2. In a means for securing window sashes 105

110

2
in position a nut, a hollow threaded member adapted to fit said nut, a plate at the forward end of said member, a recess in said plate, a flange at the forward end of said member expanded into said recess, a shoulder or offset at the forward end of the threaded portion of said member, said plate being engaged with said member between said shoulder and said flange, and a handle 10 adapted to turn said member, thereby bring-

ing said plate to bear against one of the sashes, thereby securing it in place.

3. In a means for securing window sashes in position a tubular member, a thread on the exterior thereof, a nut adapted to fit said 15 thread, a means for securing said nut to the inner sash and one end of said tubular member being expanded into a flange for bearing against the outer sash.

ISRAEL BENJAMINS.
